UNITED STATES PATENT OFFICE.

SIGRID L. M. PEARSON, OF CHICAGO, ILLINOIS.

DESIGN FOR A PHONOGRAPH-CASING.

56,026.

Specification for Design.

Patented Aug. 10, 1920.

Application filed November 17, 1919. Serial No. 338,776. Term of patent 14 years.

To all whom it may concern:

Be it known that I, SIGRID L. M. PEARSON, a citizen of the United States, residing at Chicago, in the county of Cook and State of Illinois, have invented a new, original, and ornamental Design for Phonograph-Casings, of which the following is a specification, reference being had to the accompanying drawing, forming part thereof.

Figure 1 is a plan view of a phonograph casing showing my new design; Fig. 2 is a front elevation of the same; Fig. 3 is a side elevation of the same.

I claim:

The ornamental design for a phonograph casing, as shown.

SIGRID L. M. PEARSON.
